UNITED STATES PATENT OFFICE.

GEORGE W. MCGEORGE, OF BRECKENRIDGE, AND WILLIAM C. BANKS,
OF ELBERT, COLORADO.

PLAYING-CARD.

SPECIFICATION forming part of Letters Patent No. 506,648, dated October 10, 1893.

Application filed February 21, 1893. Serial No. 463,286. (No model.)

To all whom it may concern:

Be it known that we, GEORGE W. MC-
GEORGE, residing at Breckenridge, county of
Summit, and WILLIAM C. BANKS, residing at
5 Elbert, Elbert county, State of Colorado, both
citizens of the United States of America, have
invented certain new and useful Improve-
ments in Playing-Cards; and we do declare
the following to be a full, clear, and exact de-
10 scription of the invention, such as will enable
others skilled in the art to which it appertains
to make and use the same, reference being had
to the accompanying drawings, and to the let-
ters and figures of reference marked thereon,
15 which form a part of this specification.

Our invention relates to an improved game
having for its object both instruction and
amusement. It is to be called the National
Game as it is played with cards having the
20 names of all the states and territories of a cer-
tain country printed thereon together with the
area in square miles, the population, the num-
ber of counties, while on the margin is print-
ed the names of all the adjoining or contigu-
25 ous states, or those which bound the state
whose name is on the body of the card.

This specification and the accompanying
drawings are prepared with special reference
30 to a pack of cards having the names and other
information of all the States and Territories of
the United States, printed thereon. It will,
however, be readily understood that the cards
35 may be prepared with special reference to any
other country as well as the United States
without departing from the principle of the
invention, which consists further of the fea-
tures hereinafter described and claimed all of
40 which will be fully understood by reference
to the accompanying drawings in which is
illustrated an embodiment thereof.

In the drawings, Figure 1 shows a number
of the cards arranged after the customary
manner of holding cards in the hand dur-
ing the progress of a game. In this view the
45 face of one card is fully exposed to view while
the faces of the other cards are more or less
concealed; Fig. 2 illustrates the manner of ar-
ranging the cards with reference to the
boundaries.

50 As all the matter printed on all the cards

is arranged on the same principle the descrip-
tion of one card will suffice to make all fully
understood. The face of the card represent-
ing California being fully exposed in Fig. 1,
this card will be described and from this de-
55 scription all the other cards will be understood.
Within the margin of this card and near the
top the name of the State is printed and below
this the number of counties, the name of the
capital city, the people by whom the State was
60 originally settled, date of admission into the
Union, the chief productions, the rank of the
State with reference to and its area in square
miles and its population and rank in this
respect. Upon the margin of one side is print-
65 ed the name Oregon as this is considered the
top of the card from a map standpoint. Hence
Oregon being the northern boundary of the
State its name is printed on this margin, while
on the right hand margin are the names Ne-
70 vada and Arizona since these bound Califor-
nia on the east. And for the same reason we
find the name Lower California printed on
the bottom margin, and Pacific Ocean on the
margin at the left.

75 A number of games may be played by the
use of these cards. The particular game, how-
ever, which we have in mind and which we
consider preferable may be explained as
follows:—The cards are first shuffled and an 80
equal number dealt to each player until the
pack is exhausted or until the cards are re-
duced to a number less than the number of
players. These are called odd cards and are
to be counted for the dealer. The District of 85
Columbia card counts one for the person play-
ing it, and will take any other card or any
trick. The Rhode Island card counts one for
the person playing it, as is also the case with
the Alaska card unless it is taken with the 90
District of Columbia card, and in this event
it counts for the person taking the trick. Ex-
cepting the District of Columbia card the one
representing the State having greatest area
as designated in square miles on its face, 95
takes the trick. Each card representing one
of the original thirteen States counts one for
the person having it in a trick during the
progress of the game. Each trick taken also
counts one for the game. After the cards are 100

all played each one writes down in separate columns the number of square miles, the number of the population and the number of the counties of the States represented by the 5 cards he has taken and the largest aggregate of each column counts five for the person holding the cards represented by the items of the column. Then each player examines his cards with reference to the boundaries of the 10 States represented thereby and as indicated in the margins of the cards and each of all the cards that join in this respect counts one for the holder. For instance the person holding all the cards represented in the group 15 shown in Fig. 2 would for this reason alone count six points for the game. The game is played for a certain number of points and the person getting this number first, wins.

The cards may be printed in any desired 20 colors and may be made as neat and attractive in appearance as desired. Each pack of cards should be accompanied by a suitable number of score cards, one for each player, having the rules of the game printed on one 25 side and columns with suitable headings as "Area" "Population" "Counties" formed on the opposite side. This feature will add interest to the game and greatly facilitate the writing down and computation of the items.

30 These score cards should be formed of some material which will permit the erasure of the

marks so that the same score card may be used repeatedly.

Having thus described our invention, what we claim is—

1. A pack of cards representing the divisions of a country and having the names of the divisions respectively printed on the faces of the cards, and the names of the boundary divisions on the margins of these faces, substantially as described. 35

2. A pack of cards representing the divisions of a country and having the names of the divisions respectively printed on the faces of the cards together with other information 45 as the area, population, &c., the names of the boundary divisions being printed on the margins and arranged with reference to the geographical location of the respective stations, substantially as described. 50

In testimony whereof we affix our signatures in presence of two witnesses.

GEORGE W. McGEORGE.
WILLIAM C. BANKS.

Witnesses as to signature of George W. McGeorge:

ISHAM R. HOWZE,
IRA W. TESCH.
